UNITED STATES PATENT OFFICE.

JOSEPH GRIMMER, OF GRIFFITH, INDIANA.

RAILROAD-TIE.

No. 904,061.

Specification of Letters Patent. Patented Nov. 17, 1908.

Application filed December 30, 1907. Serial No. 408,583.

To all whom it may concern:

Be it known that I, JOSEPH GRIMMER, a citizen of the United States, residing at Griffith, county of Lake, and State of Indiana, have invented certain new and useful Improvements in Railroad-Ties, of which the following is a specification.

This invention relates to railroad ties, and more particularly to metallic ties, the object 10 being to provide a tie with very novel means for securing the rail clamping plates thereon, whereby the rails will be securely locked in perfect alinement without any danger of them spreading.

Another object of my invention is, to provide a tie which is exceedingly simple and cheap in construction, and one which is very 15 strong and durable.

These objects are obtained by the novel 20 arrangement and construction of parts hereinafter fully described and shown in the accompanying drawings in which:

Figure 1, is a top plan view of my improved tie. Fig. 2, is a longitudinal section 25 of the same. Fig. 3, is a transverse section. Fig. 4, is a detail longitudinal section showing a rail secured thereon, and, Fig. 5, is a perspective view of one end portion of the tie showing a rail clamped thereon.

In the drawings 1 indicates a closed rectangular metallic shell forming the body of my improved tie, the only openings extending into the body being the core holes 1', in the bottom wall 1^a. The top 1^b is flat, and is 30 provided with spaced enlarged transverse portions or ribs 2—2', 3—3' at each side of the longitudinal center and on its under side, into which extend transverse slots 4, formed in the top, and which are provided with enlarged outer ends 4' for the purpose herein- 35 after fully described. It should be noticed that the slots do not extend or open into the body of the tie, but are closed at the bottom by walls 2^a—3' formed by the respective ribs.

Extending up from the top 1^b of the tie and toward the outer end of the tie from the enlarged portions 2 and 3 respectively, are transverse ribs 5—5', against which the outside clamping plate 6, abuts, which latter is adapted 45 to fit against the side of the rail 7, which is arranged on the top of the tie between the slots. The plate is shaped to conform to the flange and web of the rail, and is provided with spaced openings through which bolts 8, 50 are adapted to extend, the heads of the bolts being placed in the enlarged portions of the

slots 4, and then forced inwardly so as to be securely locked therein. Nuts are then screwed down on the bolts, which securely lock the clamping plate in position, so that 60 it will be impossible for the rail to move or spread. Similar bolts 9, are placed in the slots at the other side of the rail over which fits the clamping plate 10, which is also shaped to conform to the web and base of the 65 rail; and it will be seen by this arrangement the clamping plates and bolts can be readily detached when desired.

From the foregoing description it will be seen that after the bolts have once been inserted, to remove the clamping plate, it is not necessary to remove the bolts, and by simply unscrewing the nuts, the plates can be readily removed when it is desired to place in a new rail.

Having thus described my invention what I claim as new and desire to secure by Letters Patent is:

1. A railroad tie comprising a closed metallic shell having a flat top provided with 80 transverse ribs on its under side, bolt receiving slots formed in the top of said tie and extending into said ribs, bolts having their heads arranged in said slots, and clamping plates secured on said tie by said 85 bolts, substantially as described.

2. A railroad tie comprising a hollow rectangular metal shell entirely closed except for the core holes in the bottom wall, the top wall of said tie being flat and provided 90 with transverse ribs formed on its under side, bolt receiving slots formed in the top of said tie and extending into said ribs, as and for the purpose specified.

3. A railroad tie comprising a metal shell 95 having a top provided with transverse ribs on its under side, and bolt receiving slots formed in the top of said tie and extending into said ribs, said slots being closed at the bottom by a wall forming a portion of said 100 ribs, substantially as described.

4. A railroad tie comprising a metallic shell having a flat top, provided with spaced enlarged ribs on its under side and to each side of the longitudinal center, said enlarged 105 ribs being provided with slots having enlarged outer ends, bolts secured in said slots by inserting the heads into the enlarged portions of the slots, and then forcing said bolts inwardly, and clamping plates secured 110 on said tie by said bolts, adapted to engage a rail.

5. A railroad tie comprising a metallic closed shell, having transverse spaced enlarged ribs formed on the under side of its top to each side of its longitudinal center, 5 the top of said tie being provided with slots extending into said enlarged ribs, and having enlarged outer ends for receiving heads of bolts, transverse ribs formed on the top of said tie, adjacent to the outer slots, and 10 clamping plates secured on said bolts, the

outer clamping plates engaging the transverse ribs, for the purpose set forth.

In testimony whereof I have signed my name to this specification in the presence of two subscribing witnesses.

JOSEPH GRIMMER.
